UNITED STATES PATENT OFFICE.

JOHN REGAN, OF NEW BEDFORD, MASSACHUSETTS, ASSIGNOR TO CROMPTON & KNOWLES LOOM WORKS, A CORPORATION OF MASSACHUSETTS.

WARP STOP-MOTION FOR LOOMS.

951,487.

Specification of Letters Patent. Patented Mar. 8, 1910.

Application filed March 10, 1906. Serial No. 305,211.

To all whom it may concern:

Be it known that I, JOHN REGAN, a citizen of the United States, residing at New Bedford, in the county of Bristol and State of Massachusetts, have invented certain new and useful Improvements in Warp Stop-Motions for Looms, of which the following is a specification.

My invention relates to warp stop motions, and particularly to a warp stop motion of the class shown and described in U. S. Letters Patent, No. 813,765. In said patent the warp stop motion is supported by the warp threads and is movable up and down therewith in a vertical plane, and as shown and described in said patent the warp stop motion comprises lease rods, and guides for the drop devices, and warp supporting rests, and end frames for the same, all of which are supported on the warp threads. In order to overcome this excessive weight on the warp threads, coil springs are provided to act as counterbalances to lessen the weight, but in the process of weaving, the repeated formation of the sheds gives to the warp stop motion a vibratory motion up and down upon the shaft upon which it is mounted. It is found in practice that this vibratory motion, occurring at every formation of the shed, and some one hundred and fifty or more times a minute, acts by the momentum of the weight of the counterbalance springs to move the motion, beyond the movement of the warp threads themselves, and thereby stretch or strain the warp threads, and instead of obtaining the advantages to be derived from the movement of the warp stop motion with the warp threads, such vibratory motion proves detrimental to the warp threads, and to the accuracy in which the warp threads are laid in the fabric. In order to obtain the advantages desired with this patented construction of the warp stop motion, I have in my improvements combined therewith supplemental mechanism, which, as shown and described herein, comprises an arm attached to the rock shaft on which the motion is mounted, and a cam, in this instance fixed on one end of the crank shaft, to engage and move said arm; said cam makes one revolution during each movement of the harnesses to form the shed, and I preferably have the cam of such shape as to give such a move-

ment to the warp stop motion, that the 55 drop devices and warp supporting rods or rests will coincide with the movement of the warps and the drop devices, which rest on the warp threads, as said threads move to form the sheds. 66

My invention consists in certain novel features of construction of my improvements as will be hereinafter fully described.

I have only shown in the drawing a detached portion of an electric warp stop motion of the class referred to, sufficient to enable those skilled in the art to understand the construction and operation of my improvements. 65

Referring to the drawing:—Figure 1 is a 70 vertical section through a warp stop motion embodying my improvements, taken at a point indicated by line 1, 1, Fig. 2, looking in the direction of arrow *a*, same figure, and, Fig. 2 is a side view of the parts shown in 75 Fig. 1, looking in the direction of arrow *b*, same figure. The warp threads are not shown in this figure.

In the accompanying drawing, 1 is a detached portion of a loom frame or side, 2 80 a stand secured thereto and having a bearing 2' for a rock shaft 3. A hub 4 is secured on the rock shaft 3 by set screws 5, and has a boss 4' in which is adjustably secured, by a set screw 6, one end of an angle rod 7; 85 the other end of the angle rod 7 is adjustably secured by a set screw 8 in the boss 9' on the end frame 9 of the warp stop motion. Extending between the end frame 9, and an end frame on the opposite end of the warp 90 stop motion, not shown, are in this instance three warp supporting rests or rods 10, over which the warps 11 from the whip rod 12 pass. The two end frames 9 and the angle rods 7 form in this instance the supports 95 for the warp rests or rods 10. Intermediate the warp supporting rods 10, and the harnesses, not shown, are preferably two lease rods 13, which divide the warps 11 into two planes. All of the warp threads are supported on the warp rests or rods 10. The warp supporting rods and the lease rods may be arranged as shown and described in Letters Patent, No. 813,765, above referred to, 100 if preferred. 105

The drop devices 14 are arranged in two sets, and each drop device is supported on a warp thread, and has in this instance an

22
 open end slot in its lower part, and a closed slot or opening in its upper part through which extends a guide rod 15, which is secured to the end frames of the warp stop motion, and in this instance acts as one of the terminals of an electric circuit. Extending between the two sets of drop devices 14, and supported on and secured at each end to the end frames of the warp stop motion, is a bar 16, which forms the opposite terminal of the electric circuit. A wire 17 of one pole, as positive, is connected with the bar or terminal 16, and a wire 18 of the opposite pole, as negative, is connected to each of the rods or terminals 15, and said wires 17 and 18 lead to mechanism not shown, for stopping the loom in the usual and well known way.

It will be understood that upon the breaking of a warp thread, the drop device supported thereon is lowered until its side projection 14' engages the central terminal 16, as shown in Fig. 1, to close the circuit, and cause mechanism to be operated to stop the loom, in the usual and well known way. Fast on one end of the rock shaft 3 is the hub 19' of a cam lever 19, which in this instance extends in a substantial horizontal plane, with its engaging end resting on a cam 20, the hub 20' of which is in this instance secured by a set screw 21 on a driven shaft 22, see Fig. 2. The position of the cam 20 on the driven shaft 22, relative to the cam lever 19, is preferably such, that when the harnesses are in their lowered position the cam lever 19 will be engaged by the lowest part of the cam, as shown in Fig. 1, and when the harnesses are in their raised position the cam lever will be in its highest position relative to the cam lever 19, so that the up and down movement of the warp stop motion will correspond to the up and down movement of the harnesses, and thus relieve the warp threads from any undue tension or strain. It will thus be seen that by means of the cam 20, and cam lever 19, a positive vertical movement is communicated to the warp stop motion, to cause the same to move up and down with the warp threads, but such motion is entirely independent of the warp threads.

The advantages of my improvements will

be readily appreciated by those skilled in the art.

I believe I am the first to so govern the movement of the whole warp stop motion, which embraces the warp rests or rods to support the warp threads, and maintain their proper relation with the drop devices at all times, so that they will coincide in movement with the movement of the warp threads, as they form the sheds, and there is no abnormal strain put upon the warp threads due to the presence of the warp stop motion through which the warp threads are carried.

It will be understood that the details of construction of my improvements may be varied if desired, and they may be adapted to be used in connection with mechanical warp stop motions, and different classes of electric warp stop motions. Instead of a cam and cam lever, for giving a positive vertical movement to the warp stop motion, other suitable means may be used.

Having thus described my invention, what I claim as new and desire to secure by Letters Patent is:—

1. In a warp stop motion, warp rests, and drop devices, and supports for the warp rests, and means for moving said supports, to cause the warp rests and drop devices to move in coincidence with the movement of the warp threads.
2. In a warp stop motion, warp rests, and drop devices, and supports for the warp rests attached to a shaft, to have a pivotal or rocking movement, a cam lever connected with said shaft, and a driven cam to operate said lever, to cause the warp rests and drop devices to move in coincidence with the movement of the warp threads.
3. In a warp stop motion, warp rests, and drop devices, and supports for the warp rests having a pivotal or rocking movement, and means for moving said supports, to cause the warp rests and drop devices to move in coincidence with the movement of the warp threads.

JOHN REGAN.
